3,167,304
PACKAGE AGITATOR FOR INCREASING
ICE CAPACITY
Everett C. Lemmond, Rte. 3, Somerville, Ala.
Filed Oct. 17, 1962, Ser. No. 231,251
2 Claims. (Cl. 259—1)

This invention relates to the preparation and handling of perishables of various kinds in a manner to maintain them in a particular state of preservation including during shipment, and to apparatus and equipment employed in such preparation and handling of commodities of various kinds including poultry, fish, and other products.

The invention relates particularly to the placing of poultry, fish, and other commodities, some of which are used as food, in a package or container and the addition of ice for keeping the contents of the package cold during shipment and until such time as the contents of the package reach their destination, are used, or are placed in a refrigerated area.

Perishables of various kinds including poultry, fish and other substances have been placed in a carton or package with crushed ice in an effort to provide adequate refrigeration or cooling during shipment or until such time as the contents of the package can be used or placed under refrigeration, but the amount of ice has not always been adequate and at times spoilage and loss of the product has occurred.

It is an object of the invention to provide means for increasing the amount of ice in crushed or small particle form placed in the package or container with perishable products sufficient to provide the necessary refrigeration during transportation or from the time the product leaves the shipper until it is received.

Another object of the invention is to provide an agitator by which spaces between poultry or other products shipped can be more completely filled with ice to provide additional refrigeration over that ordinarily provided thereby obtaining greater success and less loss in the shipment and delivery of comestibles and other perishable products.

Other objects and advantages of the invention will be apparent from the following description taken in conjunction with the accompanying drawing wherein:

FIG. 1 is a perspective illustrating one application of the invention including a table or support and a shaker or agitator;

FIG. 2, a horizontal section along the lines 2—2 of FIG. 1;

FIG. 3, an enlarged fragmentary detail section through the rollers along the line 3—3 of FIG. 1;

FIG. 4, a horizontal section on the line 4—4 of FIG. 1 showing the motor drive;

FIG. 5, a perspective of the eccentricity adjustment;

FIG. 6, an enlarged fragmentary detail showing the connection through the table; and

FIG. 7, a vertical section on line 7—7 of FIG. 5.

Briefly stated the invention is a support for packages, boxes, cartons or the like, in which poultry or other perishable products are shipped, and in which ice is added to and distributed throughout the mass of the product within the container. The support includes a platform having rollers to facilitate the movement of a box, carton or the like container of a perishable product to which ice is to be added, such platform being of generally rectangular form, centrally and transversely supported, for oscillatory motion, upon a table or other base, the upper surface of the latter of which is inclined from such transverse central support, so that when ice is discharged into the box or carton with the perishable material to be refrigerated, any ice which does not go into the container

2

will not accumulate on the table sufficiently to interfere with the agitation of the package or container. In order to produce agitation or vibration of the platform a motor and an eccentric are employed with means whereby the amount of agitation or vibration can be varied or adjusted to suit.

With continued reference to the drawing a platform frame 10 is provided of a generally rectangular configuration in which a plurality of spaced rollers 11 are mounted on transverse shafts 12. The ends of the shafts are located in openings 13 in the frame 10 and a series of spacing sleeves 14 are located between the rollers to maintain them in proper relation.

If desired the frame may have a reinforcing center brace 10' provided with openings 13' in which the shafts 12 are received.

In order to prevent the shaft 12 from endwise movement a retainer bar 15 is disposed on the exterior of each side member of the frame, such bar being secured in place by bolts or other fasteners 16.

The platform or support formed by the frame 10 with the rollers 11 incorporated on shafts 12 is adapted to receive boxes, cartons, or other containers with perishable matter therein to which ice in crushed or lump form is adapted to be added to provide the necessary refrigeration or cooling effect throughout transportation and delivery of the container.

Ice may be supplied in any desired manner and during which time according to the present invention the container is adapted to be agitated or vibrated to cause a more intimate association or compacting of the perishable substance and the ice, to give an added margin of preservation to the product.

In order to provide agitation or vibration the frame 35 and associated rollers and shafts are supported by spaced brackets 17, secured by fasteners 18, to the frame and mounted on spaced pivots 19 midway between the ends of the frame for balance and to require minimum effort in the oscillation or agitation of the package supported.

40 The pivots 19 are mounted at opposite sides and across the center of a supporting table having an impervious top shield member having surfaces 20 and 21 inclined downwardly from the pivot 19 area and extending the length and width of the table, in order that ice which does not find its way into the container and falling onto the inclined surfaces 20 and 21 of the table, will not accumulate sufficiently to interfere with the operation of the device.

45 The table is provided with legs 22 and a horizontal rigidly mounted platform 23 attached thereto and on which a motor 24 is adapted to be supported for producing oscillation or agitation of the platform and supported container.

In order to provide a drive between the support frame 55 for a container to be shaken and the motor, the motor shaft 25 has fixed thereon a pulley 26 which drives a belt 27 around a larger pulley 28 mounted on a shaft 29. The shaft 29 is mounted in a bearing on a cross member 31 supported at one end on side bars 32 attached to the legs 22 of the frame and at the other end on platform 23. Drive by the shaft 29 is transmitted through an adjustable connection including a generally rectangular plate 33 rigidly attached to said shaft and extending across its end at right angles thereto.

60 This plate has side bars or rails 34 against which there is adapted to be fastened a plate 35 in which is mounted a nut and bolt which form a shaft 36. A bearing 37 is interposed between the shaft and the plate 35 and around the shaft 36 is disposed a sleeve 38 fixed to a connecting rod 39 which extends through an aperture in the inclined surface 20 at one end of the table as shown in FIGS. 1 and 6. The connecting rod 39 has a bearing sleeve 40

which engages a bracket 41 attached to the intermediate frame member 10'.

The plate 35 is provided with corner openings 42 for receipt of bolts and nuts 43 which are adapted to be adjustably received in corner slots 44 parallel to the side rails 34. The slots 44 permit adjustment of the shaft forming bolt 36 eccentrically relative to the shaft 29 driven by the motor, and the degree of the eccentricity of the shaft 39 from the shaft 29 determines the movement and vibration of the platform.

It will be readily understood that a simple, practical, low-cost agitator is provided by means of which a greater density may be obtained within a package or container without additional labor and in effect reducing the amount of labor required in the supplying of ice to the container initially in that all the empty spaces are entirely filled.

If desired guide rails 45 and 46 may be mounted at each side of the platform frame 10, such guides preferably having curved ends in proportion to facilitate introduction of a container or carton therebetween and such guides are supported on frame 10 in vertically spaced relation thereto by means of brackets 47.

If desired removable ice excluding side walls or shields 48 may be provided which can be secured in place to the sides of the table at 49, and brackets 50 may be provided for the attachment of delivery and discharge conveyors at the ends thereof for incorporation in a conveyor system.

It will be obvious to those skilled in the art that various changes may be made in the invention without departing from the spirit and scope thereof and therefore the invention is not limited by that which is illustrated in the drawings and described in the specification, but only as indicated in the accompanying claims.

What is claimed is:

1. A food container agitator machine adapted for use in a package conveyor system for guidingly receiving containers of poultry or the like and of a construction by which a shaking action of adjustable intensity may be imparted to the containers for effecting increased ice chip container volume through compaction effected by such shaking action, said machine comprising a supporting table structure having means thereon for correlating it within a conveyor system, an elongated generally rectangular load-bearing platform mounted on and above said supporting table structure in vertically spaced relation thereto for pivotal movement of the platform about a horizontal axis approximately midway of the length thereof, said axis extending transversely of said table and parallelly spaced below said platform, a motor mounted below said platform and on said table for oscillating said platform, motor-driven linkage means of adjustably variable length connected to one end of said pivoted platform to effect controlled oscillatory shaking thereof, said platform comprising an open structure having a peripheral frame, series of relatively widely spaced rollers rotatively mounted within said peripheral frame and in the plane of said platform throughout the area thereof on transversely extending parallel axes thereby forming a platform spacial-roller load-bearing surface, platform guide rail members mounted on said platform in vertically spaced relation thereto and along the parallel opposite sides of said platform and adapted to prevent lateral displacement of containers on said platform while being subject to said controlled oscillatory shaking, said supporting table structure including a shielding impervious top surface member thereon extending substantially the length and width

thereof beneath said platform, said impervious top surface shielding member being inclined downwardly in opposite oblique planes to adjacent the opposite ends of said table from an elevation located above the pivotal mounting of said platform whereby when said platform is pivotally agitated any ice chips or the like spilled onto said platform will fall freely between said spaced platform rollers onto said oppositely inclined table top member so as to be enabled to slide therefrom under the action of gravity to effectively prevent such spillage damaging and interfering with the operation of the machine.

2. A machine for guidingly receiving a container of poultry mixed with ice and of a construction by which a shaking action may be imparted to the iced poultry to obtain greater compactness and consequently greater container ice capacity, said machine comprising a support structure having means thereon for correlating it within a conveyor system, a generally plane platform having parallel sides positioned above said support structure, means disposed substantially midway the length of said platform providing pivotal support therefor on said support structure about an axis spaced from the plane of said platform, said platform comprising an open frame structure, means pivotally mounting series of relatively widely spaced rollers throughout the entire area of said platform frame on parallel axes extending transversely thereof to provide rotational and spaced load-supporting surfaces thereon for movement of containers adapted to be positioned thereon lengthwise thereof, rails mounted on the longitudinally extending sides of said platform for preventing lateral displacement of containers from said platform, a motor mounted on said supporting table below said platform, motor-driven adjustable linkage means connected to one end of said pivoted platform to effect pivotal oscillation thereof of controlled intensity, an impervious top surface member on said supporting table extending substantially the length and width thereof beneath said open platform, said impervious top surface member being inclined downwardly in opposite oblique planes to adjacent the edges thereof from an elevation located above the mid-pivotal mounting of said open platform whereby when said open platform is pivotally oscillated any ice or the like spilled onto said platform will fall freely between said relatively widely spaced platform rollers onto said oppositely inclined table top member so as to be enabled to slide therefrom by the action of gravity to effectively prevent such spillage from interfering with the operation of the machine.
